UNITED STATES PATENT OFFICE.

GEORGE W. VETTER, OF COMMERCE, MISSOURI.

SHOCKING ATTACHMENT FOR GRAIN BINDERS.

Application filed May 12, 1925. Serial No. 29,790.

This invention relates to shocking attachments for grain binders and has for one of its principal objects the provision of simple means whereby a number of bundles 5 of grain may be collected to form a shock, which shock is dumped on end at the rear of the machine by a mechanism which is under the entire control of the operator.

A further and equally important aim of 10 the invention is to provide a shocking attachment for grain binders having simple means whereby the same is automatically returned to its bundle receiving position upon dumping a shock.

15 A further aim of the invention is to provide a shocking attachment for grain binders which may be conveniently applied to a binder without substantially altering the construction of the binder and without increasing the turning radius of the binder, 20 all of which greatly contributes to the practicability and desirability of the invention.

Other objects and advantages will be apparent during the course of the following 25 description.

In the accompanying drawings forming a part of this application and in which like numerals are employed to designate like parts throughout the same,

30 Figure 1 is a fragmentary perspective of a grain binder equipped with the improved shocking attachment;

Fig. 2 is a detail elevation illustrating the 35 operating mechanism by means of which the shocking attachment is moved to discharging position by the operator and automatically returned to a bundle receiving position;

Fig. 3 is a vertical sectional view through 40 the shocking attachment in its bundle receiving position;

Fig. 4 is a vertical sectional view through 45 the shocking attachment, the basket or carrier for the various bundles being shown partly moved to its discharging position;

Fig. 5 is a fragmentary plan view illustrating the bundle carrier of the shocking attachment in its discharging position;

Fig. 6 is a fragmentary plan view of a 50 clutching mechanism embodied in the invention and by means of which a driving connection is established between a moving part of the binder and the shocking attachment;

55 Fig. 7 is a detail sectional view taken on line 7-7 of Fig. 6;

Fig. 8 is a group perspective of one of the sections of the bundle carrier and the holding means therefor.

In the drawings, wherein for the purpose 60 of illustration is shown a preferred embodiment of the invention, the numeral 10 generally designates a binder or harvesting machine having the usual discharge tray or chute 11 over which the bundles of grain 65 pass in the usual and well known manner. As previously stated, the invention forming the subject matter of this application resides in the means for collecting a number of the bundles upon being discharged from the tray 70 11 and discharging these bundles as a unit or a shock at the end of a predetermined interval.

The attachment comprises a pair of beams 75 12 adapted to be secured to the binder as shown in Fig. 1 and extend out to one side of the binder to support the movable carrier into which the bundles are introduced.

Figs. 3, 4 and 5 illustrate that the carrier body 14 has a basket 15 and a closure 16 80 hingedly connected thereto and when the carrier is in its receptive position as shown in Fig. 3 a flange or extension 17 on the forward edge of the basket 15 may rest upon a cross member 18 of the carrier. Of course, when the carrier is in its receptive 85 position the closure 16 is in its elevated position so as to permit of the entrance of the bundles into the basket. However, when the carrier starts its movement to discharge position, the closure 16 is moved to the position illustrated in Fig. 4 so as to prevent the discharge of the shock before the carrier reaches its discharge position.

The body 14 is provided with a rearward 90 extension or attaching portion 20 having spaced ears which are hinged as indicated at 21 to the crank 22 on the end of a stub shaft 23. The attaching portion 20 is 95 slideable on a main guide strip or member 26 extending substantially concentrically about the shaft 23 and adapted to guide the body 14 from the position shown in Fig. 3 to the position shown in Fig. 5. It will be seen that the body 14 has a movement of 100 about 270 degrees on the member 26. The connection of the attaching portion 20 to the crank 22 by the pivot pin 21 (Figures 3, 4 and 5) serves a very important function. This connection enables the guide member 105 26 to throw the attaching portion 20 to the bundle receiving position shown in Figure 110 7.

3 wherein the flange 17 of the member 15 rests upon the cross member 18. The attaching portion 20 at this time lies in a plane parallel to the axis of the crank 22 and stub shaft 23. However, when crank 22 is rotated the guide 26 acts upon the attaching portion 20 to swing it outwardly as shown in Figures 4 and 5 so that in the final position (Figure 5) the portion 20 will appear as an extension of the crank 22 and the bundle engaging portions 15 and 16 will be thrown outwardly far enough to clear the frame 12. It is evident that if the relative positions of crank 22 and attaching portion 20 remained as shown in Figure 3 the basket portions 15 and 16 would knock against the frame 12. Applicant's arrangement is a very compact and desirable structure as above pointed out.

20 The basket portion 15 of the carrier has an arm 28 slideable on an arcuate track 30 having a greater radius than the radius of the member 26 and adapted to swing the basket from its open position shown in Fig. 3 to its closed position shown in Fig. 4 and then return the basket to its open position as shown in Fig. 5 for discharging the collected bundles. The arm 28 has a limited sliding connection transversely of the arcuate track 30 to provide for the necessary movement of the basket.

25 The closure 16 of the carrier is provided with an arm 33 slideable on an arcuate track 34 having a smaller radius than the radius of either the track 26 or the track 30 and arranged eccentrically with respect to the same to bring about the swinging of the closure with respect to the body so that the closure will assume the three positions illustrated in Figs. 3, 4 and 5. The drawings clearly illustrate that the ends of the tracks 26, 30 and 34 are secured in any suitable manner to the adjacent beam 12.

30 The shaft 23 has connection with a drive shaft 40 through the medium of intermeshing gears 41 and the outer end of the drive shaft has connection with a crank 42 which rocks in a predetermined arc. It is important to note that the crank 42 does not describe a complete circle at any time. It merely rocks somewhat less than 180 degrees and, therefore, provides for the movement of the carrier to discharge position and the return of the carrier to a receptive position. In other words, the movement of the crank 42 in one direction somewhat less than a half turn causes the shaft 23 to partake of approximately a three-quarter turn to move the carrier to discharge position and on the return of the crank 42 the carrier moves back about three-quarters of a turn to a receptive position.

35 The crank 42 is operated by a pitman rod 44 connected to a pin 45 eccentrically mounted on a disk 46 driven by a counter-

shaft 47. The shaft 47 rotatably supports a sprocket wheel 50 about which a drive chain is extended. Of course, the drive chain may extend from any turning part on the binder so as to constantly rotate the sprocket wheel. A clutch member 52 is keyed or otherwise secured to the shaft 47 and is provided with a locking lever or pawl 53 which extends into the sprocket wheel 50 and engages internal teeth on the sprocket wheel 50 to establish a driving connection between the wheel 50 and the member 52. However, the driving connection between the parts 50 and 52 may be broken by the operation of a rod 55 having a laterally directed terminal portion 54 which may be moved into engagement with the outer terminal portion of the pawl 53 whereby to remove the pawl from engagement with the internal teeth in the wheel 50. The rod 55 extends from a suitable point of control and when it is desired to establish a driving connection between the members 50 and 52 to bring about the discharge of the collected bundles, it is merely necessary to operate the member 55 to allow the pawl 53 to move into engagement, under the influence of a coil spring 56, with the internal teeth of the sprocket wheel 50. This brings about the turning of the wheel 46 and the back and forth movement of the pitman rod 44 whereby the carrier is moved to discharging position and is then returned to a receptive position.

40 With reference to the foregoing description taken in connection with the accompanying drawing it will be seen that a shocking attachment constructed in accordance with this invention may be easily applied to a binder and will be positioned somewhat to one side of the binder and will discharge the collected bundles at the rear of the machine so as not to interfere with any of the parts of the machine. When the collected bundles are dumped as a unit at the rear of the machine they are discharged on end and remain in that position. It might be added that the carrier is slightly tapered toward one end so that the shock will be narrower at the top than at the bottom whereby the shock will remain in an upright position when discharged.

45 In the normal operation of the improved shocking attachment, the carrier is first positioned as shown in Fig. 3 to receive the bundles as they pass down over the tray 11. When the basket has been filled or substantially filled the operator will establish a driving connection between a moving part of the binder and the eccentric driving pin 45 whereby the carrier is closed and is swung over to discharging position.

50 When the carrier is moved to the open position as shown in Fig. 5 it will discharge the bundles and will then start on its return

to a receptive position as shown in Fig. 3. It is important to note that the return of the carrier to a receptive position is accomplished without a further adjustment of the driving mechanism for the attachment and, therefore, it might be said that the return of the carrier is automatic.

As the improved shocking attachment is not not supported by separate wheels provided for the purpose, the turning radius of the binder is not in any way increased, this permits the binder to make a short turn at the end of the field.

Having thus described the invention, what is claimed is:

1. A shocking attachment for harvesting machines comprising a frame having means whereby the same may be secured to the harvesting machine, a carrier having a body and a pair of bundle receiving members hingedly connected to the body and provided with actuating arms, arcuate guide members carried by said frame and engaging said actuating arms, means for moving said carrier in an arcuate path, and the guide members being shaped to act upon said actuating arms to spread the bundle receiving members to their open bundle receiving or discharging position at each end of the path of movement of the carrier.

2. A shocking attachment for harvesting machines comprising a carrier having a body and bundle receivers hinged to the body and provided with arms, a drive shaft having a pivotal connection with the body and adapted to move the body in an arcuate path, arcuate guides connected to said body and to said arms to guide and actuate the receivers from open position to closed position and then to a discharging position, and means to rock said drive shaft.

3. A shocking attachment for harvesting machines comprising a carrier having a body provided with an attaching portion and bundle receivers hinged to the body and provided with arms, arcuate guide members having connection with said attaching portion and said arms to move the same from open position to closed position, and a rock shaft connected to said body.

4. A shocking attachment for harvesting machines comprising a frame, a shaft connected to the frame and having a crank, a carrier having arms and a body provided with an attaching portion pivoted to said crank, arcuate guide members extended through said attaching portion and said arms and being converged toward the ends thereof whereby the approach of the carrier to the ends of its movement will be accompanied by a movement of the carrier to open position.

5. A shocking attachment for harvesting machines comprising a frame having means whereby the same may be secured to a har-

vesting machine, a drive shaft carried by the frame and having a crank, a carrier having a body provided with an attaching portion pivoted to said crank, said carrier also being provided with a pair of bundle receivers hinged to said body and provided with arms, arcuate guides connected at the ends thereof to said frame and having connection with said attaching portion and said arms, the end portions of said arcuate guides being converged whereby the bundle receivers are moved to open position at the ends of their path of travel.

6. A shocking attachment for harvesting machines comprising a frame having means whereby the same may be secured to a harvesting machine, a drive shaft carried by the frame and having a crank, a carrier having a body provided with an attaching portion pivoted to said crank, said carrier also being provided with a pair of bundle receivers hinged to said body and provided with arms, arcuate guides connected at the ends thereof to said frame and having connection with said attaching portion and said arms, the end portions of said arcuate guides being converged whereby the bundle receivers are moved to open position at the ends of their path of travel, and means connected to said drive shaft to turn the drive shaft in one direction to move the carrier to discharging position and to automatically reverse the shaft to return the carrier to a receptive position.

7. A shocking attachment for harvesting machines comprising a frame having means whereby the same may be secured to a harvesting machine, a drive shaft carried by the frame and having a crank, a carrier having a body provided with an attaching portion pivoted to said crank, said carrier also being provided with a pair of bundle receivers hinged to said body and provided with arms, arcuate guides connected at the ends thereof to said frame and having connection with said attaching portion and said arms, the end portions of said arcuate guides being converged whereby the bundle receivers are moved to open position at the ends of their path of travel, means connected to said drive shaft to turn the drive shaft in one direction to move the carrier to discharging position and to automatically reverse the shaft to return the carrier to a receptive position, and a clutch associated with said means.

8. A shocking attachment for harvesting machines comprising a frame having means for connection to the machine, a bundle carrier having a body, a rotatable crank having pivotal connection with said body, an arcuate guide member carried by said frame and engaging said carrier body in its movement upon rotation of said crank, said frame having a member for supporting said carrier

when it is in bundle receiving position, and said arcual guide member being so shaped as to swing said carrier body laterally to substantial alinement with said crank in its movement from receiving to discharging position whereby the carrier will be extended beyond said frame when in discharge position.

9. A shocking attachment for harvesting machines comprising a frame having means for connection to the machine, a bundle carrier having a body and bundle receivers hinged to the body, a rotatable crank having pivotal connection with said body, an arcual guide member carried by said frame and engaging said carrier body in its movement upon rotation of said crank, said frame having a member for supporting said carrier when it is in bundle receiving position, said arcual guide member being so shaped as to swing said carrier body laterally to substantial alinement with said crank in its movement from receiving to discharging position whereby the carrier will be extended beyond said frame when in discharge position, and means for opening said bundle receivers at each end of the path of travel of the carrier.

10. A shocking attachment for harvesting machines comprising a frame having means for connection to the machine, a bundle carrier having a body and bundle receivers hinged to the body, a rotatable crank having pivotal connection with said body, an arcual guide member carried by said frame and engaging said carrier body in its movement upon rotation of said crank, said frame having a member for supporting said carrier when it is in bundle receiving position, said arcual guide member being so shaped as to swing said carrier body laterally to substantial alinement with said crank in its movement from receiving to discharg-

ing position whereby the carrier will be extended beyond said frame when in discharge position, and means for opening said bundle receivers at each end of the path of travel of the carrier, supplemental guide members for said bundle receivers, said guide members being arranged and operatively connected to said bundle receivers whereby to actuate the same to open position at each end of the path of movement of said carrier.

11. A shocking attachment for harvesting machines comprising a frame having means for connection to the machine, a bundle carrier having a body, a rotatable crank having pivotal connection with said body, an arcual guide member carried by said frame and engaging said carrier body in its movement upon rotation of said crank, and said arcual guide member being so shaped as to swing said carrier body laterally to substantial alinement with said crank in its movement from receiving to discharging position whereby the carrier will be extended beyond said frame when in discharge position.

12. A shocking attachment for harvesting machines comprising a carrier having a body and bundle receivers hinged to the body, guide means for supporting said body for movement in an arcuate path and having engagement with said bundle receivers whereby to open or spread the same at each limit of movement of the carrier, a drive shaft having a crank end engaging said carrier whereby to move the same in an arcuate path, an oscillatory shaft, connecting gearing between said drive shaft and said oscillatory shaft, the latter having a crank at its end, and a rotatable drive member and a pitman connection between the same and the crank of said oscillatory shaft.

In testimony whereof I affix my signature.

GEORGE W. VETTER.
